COACH CONSTRUCTION

Harold E. Fox, Pontiac, Mich., assignor to Yellow Truck & Coach Manufacturing Company, Pontiac, Mich., a corporation of Maine

Application February 3, 1939, Serial No. 254,341

5 Claims. (Cl. 280—106)

This invention relates to motor vehicles and more particularly to an improvement in base frame structures. Road vehicles as usually constructed have the body carried on a main frame which consists essentially of two heavy longitudinal members extending from front to rear and the running gear supports the frame through shackle brackets mounted directly on the main longitudinals. As distinguished from the conventional the present invention is concerned with a structure in which the main chassis frame is eliminated and wherein the body side walls and roof cooperate in forming a load carrying truss from which the load is transmitted through front and rear bucks to the road gear. Accordingly the floor is supported upon a series of longitudinally spaced cross member assemblies, each joined at opposite ends to the body side walls, with those cross members immediately adjacent the front and rear axles mounted on the axle springs.

An object of the invention is to provide an under floor or base frame which can be made up in the ordinary shop without expensive equipment from low cost standard section and light weight parts and assembled as to have a high degree of strength and torsional rigidity. To keep down weight the several framing elements may be formed from aluminum or other similar metals.

Another object is to provide an open truss cross member having considerable height corresponding substantially with the depth of the wall skirt so that its connection with the wall is over a larger part of the vertical dimension of the wall for mutual reinforcement and resistance to torsional stress.

A further object is to provide a cross member whose parts can be brought together in a bench fixture and joined as a sub-assembly thereby eliminating confusion and reducing the number of operations on the final assembly line.

A still further object of the invention is to provide a base frame construction which can be readily and quickly assembled by bringing together the required number of cross member units to form the front and rear bucks and joining them in proper spaced relation by longitudinal tie bars whose primary function is that of spacers but which also may be arranged for co-operation with the axle mounted cross members in imparting stiffness thereto.

Additional objects and advantages will become apparent during the course of the following specification having reference to the accompanying drawings wherein Figure 1 is a perspective view

of the base frame with the body outline illustrated by broken lines. Figure 2 is a top plan view of the frame; Figures 3 and 4 are side elevations on a larger scale of the end portions of the frame as viewed in the direction of the arrows on lines 3—3 and 4—4 of Figure 2; Figures 5 and 6 are elevations of certain of the cross member assemblies with parts in section on lines 5—5 and 6—6, respectively, of Figure 2 and Figure 7 is a detail view of an alternative rear end construction.

The vehicle illustrated is a motor coach for operation on the highway and is of the type driven either by an electric motor or by an internal combustion engine mounted at the rear for driving the rear set of wheels and being under control of an operator seated at the front. The rear end construction illustrated in Figures 2 and 3 is intended for supporting an electric motor while that of Figure 7 is designed for supporting an internal combustion engine. In either event the power plant is contained within a compartment between the body rear wall and a forwardly spaced bulkhead indicated at 1. The bulkhead is in the nature of a flat metal plate stiffened by certain angle straps as, for example, the transverse strap 2 which also provides a seating ledge for the rear end of the floor 3. At opposite ends the bulkhead 1 is joined to the side legs of a U-shaped rear bumper channel 4. These side legs extend forwardly of the bulkhead and are connected to the opposite ends of a cross member assembly immediately ahead of the bulkhead. The additional cross member assemblies are located at spaced intervals throughout the length of the vehicle with that at the front constituting a forward bumper to which is connected the body front wall. The front bumper sub-assembly includes a pair of vertically spaced and forwardly arched upper and lower rails 5 and 6 joined together by vertically disposed and transversely spaced plates. The transverse rails made of angle section stock cut to proper length have their vertical flanges riveted to the top and bottom edges of the connecting plates. As best seen in Figure 1 the connecting plates comprise a centrally disposed plate 7, a pair of end plates 8 and 9 and a pair of intermediate plates 10 and 11, the endmost plates having rearwardly extending flanges for attachment to corner posts or other body structure.

At longitudinally spaced intervals between the front and rear walls are the several cross member sub-assemblies indicated in the drawings at A, B, C, D, E, F, G and H which carry the flooring

3 and are joined at opposite ends with the body side walls with the A and B cross members mounted on opposite ends of the load supporting leaf springs of the front axle assembly and F and G cross members mounted on the opposite ends of the springs in the rear axle assembly. Thus the running gear receives the load from the front and rear sets of cross members A—B and F—G, respectively, with the floor load on the remaining 10 cross members being transmitted through the body walls. It may be noted here that variation in the number of intermediate cross members enables the vehicle to be of whatever overall length is desired.

15 In each instance the cross member sub-assembly is in the nature of an open truss affording considerable depth and rigidity without undue weight and also providing free passage of the necessary control rods, pipe lines, wiring cables 20 and the like. At the top and bottom of each truss are transversely extending rails, preferably of structural section shape, the floor rail being illustrated as of T-section and the bottom rail of L-section with flat gusset plates riveted to the 25 vertical flanges of the rails at transversely spaced intervals and certain of the neighboring plates being additionally jointed to short length diagonal bars of angle section. Only standard stock parts are needed and these are simply cut to size with- 30 out bending or machining operations.

Inasmuch as the cross members do not differ essentially from one another the drawings show only the members F and G on an enlarged scale. Referring first to the cross member F in Figure 6 35 the upper or T-section rail on which the flooring rests is indicated at 12 and the lower or L-section rail at 13. Their ends at the left in Figure 6 have riveted to the vertical flanges a gusset plate 14 which extends slightly beyond the rails for attachment with an adjacent body post in the side wall of the vehicle. A similar gusset plate 15 connects the opposite ends of the rails and provides for attachment with a body post in the other side wall of the body. The side wall attachments extend throughout the depth of the 40 wall skirts and insure firm and secure fastenings. At the vehicle center line the vertically spaced rails are tied together by an angle strap 16 riveted to upper and lower end plates 17 and 18, each in 45 turn riveted to the vertical rail flanges. Between the center strap 16 and the end plate 14 are a pair of vertical plates 19 and 20 riveted at opposite ends to the upper and lower rails and spaced apart a given distance for a purpose to be referred to. A similar set of plates 21 and 22 connect the rails intermediate the strip 16 and end 50 plate 15.

55 For additional rigidity diagonal braces can be incorporated in the cross members as a part of the sub-assembly and are illustrated as an inwardly and upwardly extending angle strap 23 riveted at opposite ends to the plates 14 and 19; a downwardly and inwardly extending angle strip 24 riveted at opposite ends to the plates 20 and 18; a downwardly and inwardly extending angle strap 25 riveted at opposite ends to the plates 18 and 21 and an upwardly and inwardly extending angle strap 26 riveted at opposite ends to the plates 22 and 15. Also as a part of the sub-assembly operations corner gusset plates may be 60 added to the plates 19, 20, 21 and 22 adjacent the intervening space between the two plates of each set. These additional plates are not to be seen in Figure 6 because they occur on the far side of 65 the structure but they are shown in other views 70

as for example in Figure 3 where the numeral 21 indicates a corner gusset plate riveted to one flange of an attaching angle or corner piece 28 whose other flange is riveted to the plate 22. The same reference characters are applied to similar 5 parts in Figure 5 and elsewhere.

The F-cross member structure just described may be the same for all cross members A to H, inclusive, although variations may be introduced to fit particular installations. Among other 10 things the inclination of the diagonal braces may be reversed in some of the cross members, for example, in the cross members C, D and E which transfer their load into the body side walls. Variations are also incorporated in the cross 15 member G as seen in Figure 5 because of the rear end electric motor drive installation. The difference is merely in the addition of a motor supporting assembly at the center of the cross member consisting of a mounting shelf or plate 29 riveted at one side to a corner gusset plate 27 and at its opposite side to a similar plate 30 carried by an angle strap or corner piece 31. The angle straps at opposite sides of the shelf 29 are riveted to the top and bottom rails and reinforced by suitable 25 gusset plates 32. A gusset plate 33 and angle strap mounting 34 is located in spaced relation with the plate 30 for cooperation therewith as will be later described and a diagonal brace 35 is riveted to both angles 31 and 34 at one end and 30 to the plate 20 at the opposite end. Gusset plates 30 and 33 are also incorporated in the H-cross member.

In final assembly the several cross members are placed in proper longitudinal succession and preferably are clamped in a suitable locating fixture and then are tied together by inserting through the several cross members and within the spaces between the plates 19 and 20 and plates 21 and 22 a pair of longitudinal rails or bars 36 and 40 37 which are then secured by rivets to the several corner plates 27 immediately beneath the transverse floor rails 12. For stiffness the longitudinal ties are of channel section with the web at the top for a smooth upper surface and the dependent flanges at each side receive the fastening rivets joining the two side plates at each cross member. The drawings show the longitudinal ties 36 and 37 extending continuously between the front and rear body walls but as an optional 45 construction they may be made in sections to join only certain of the cross members at the front and certain of those at the rear in which case the base frame would consist of two independent end bucks over the front and rear axles and 50 joined only through the body walls. Supplemental tie sections 38 and 39 at the front and 38' and 39' at the rear may be employed to increase 55 resistance to frame twist. These also are of channel section and are received within the openings of the cross members with their side flanges riveted to the gusset plates 27—27 below and in vertically spaced relation with the main tie bars 36 and 37. The supplemental tie sections 38 and 39 in the forward buck extend from the front 60 bumper to the C-cross member and the sections 38' and 39' in the rear buck extend from the 65 E-cross member either to the rear bumper channel as in Figure 3 or to the bulkhead 1 as in 70 Figure 7.

At the front ends the ties 37 and 39 are joined through a pair of gusset plates and corner angles to the plate 10 of the front cross member assembly and similar gusset plates and corner angles 75 secure the front ends of the ties 36 and 38 to 75

the plate 11. Gusseted at opposite ends to the plate 1 and to the central portion of the A-cross member is an auxiliary rail 40 from the underside of which extends downwardly and forwardly a diagonal brace 41 to be secured to the lower rail 6 of the front cross member with forwardly projecting apertured portions 42 to provide a tow hook attachment as best seen in Figure 4. A pair of transversely extending Z-section bars 43 are riveted on the upper face of the rails 40 and 36 to provide a mounting support for the vehicle controls.

Beyond the rear or H-cross member the longitudinal tie rails as seen in Figure 3 project through openings in the bulkhead 1 and to which they are suitably fastened and are anchored to the rear bumper channel 4 by means of gusset plates 44. Similar gussets fasten to the bumper 4 the rear ends of a pair of superposed supplemental tie rails 45 and 46 which extend forwardly through the bulkhead 1 and H-cross member and are fastened at their front ends to the G-cross member by the plates 30 and 33 as seen in Figure 5. Where an internal combustion engine is to be mounted transversely within the power plant compartment the several longitudinal ties will end at the bulkhead as seen in Figure 7 and a number of rails 47 will bridge the space between the lower edges of the bulkhead 1 and cross member 4 to afford a supporting cradle for the engine.

Over the front axle the lowermost tie rails 38 and 39 are humped upwardly (see Figure 4) for axle clearance and in compensation the upper rails 36 and 37 are also bowed upwardly so that their top surface between the A and B cross members is even with the underside of the floor and the upper surface of the several T-section rails 12. To provide floor support between the rather widely spaced A and B cross members a pair of bars 48 extend transversely across and are riveted at opposite ends to the innermost flanges of the rails 36 and 37. To the outermost flange of each longitudinal tie rail is riveted (see Figure 4) a wheel housing plate 49 which extends across the space between the upper rail and its cooperating lower rail and also is riveted to the lower rail. Its length is such as to tie the upper and lower rails together throughout the whole of the distance separating the A and B cross members so as materially to stiffen the parts in the region where the load is transmitted into the running gear. A continuation of the plate above the uppermost tie rail forms a closure for the inner end of the wheel housing or well and it is bounded by angle straps 50 for connection with the curved housing which extends laterally to the body side wall. On the outer face of the stiffening plate 49 are secured by certain of the fastening rivets the plate brackets 51, 52 and 53. Brackets 51 and 53 are for mounting spring bumper pads while the bracket 52 is for the attachment of an axle shock absorber.

Similar stiffening plates 54 (see Figure 3) between the F and G cross members are riveted to the outer faces of the vertically spaced tie rails, each having an upward extension for closing the inner end of the wheel housing. Here again both tie rails are offset upwardly for axle clearance and spaced cross bars 55 provide floor support between the F and G cross members.

For mounting the cross members on the opposite ends of the transversely spaced leaf springs associated with the front and rear axles, shackle

brackets 56 of cast aluminum are provided. These brackets are of U-shape in transverse section to straddle or fit on opposite sides of the longitudinal tie bars in the corners at the respective cross members. By lateral flanges at each side they are bolted or otherwise fastened to the gusset plates 19-20 or 21-22 as the case may be and for additional anchorage the side wings may also be bolted to the longitudinal tie rails so that the shackle brackets assist in affording effective corner joints between the main load carrying members and the tie rails at points of load concentration.

I claim:

1. In a vehicle construction, a base frame including front and rear bucks each comprising a pair of longitudinally spaced cross members and each cross member including a pair of vertically spaced transverse rails extending across the vehicle from side to side, end gusset plates connecting said rails, and additional rail connecting plates spaced inwardly of said end plates, a pair of transversely spaced longitudinal tie members between said cross members, each including a pair of vertically spaced rails joined to said inward plates and a vertically disposed stiffening plate connecting the longitudinal rails, and spring hanger brackets straddling said longitudinal tie members and mounted on said inward gusset plates of the cross members.

2. In a vehicle base frame, a pair of cross member assemblies adapted for supporting connection at opposite ends with the vehicle side walls, each assembly including a pair of vertically spaced rails and vertical plates connecting the rails at spaced intervals, means associated with said assemblies for supporting connection with vehicle road gear, longitudinal tie structure positioned inwardly of both ends of said cross member assemblies, each tie structure including a pair of vertically spaced bars secured by corner gusset plates to cross member plates and a wheel housing closure plate secured to both bars to afford torsional stiffness thereto.

3. A vehicle base frame including a pair of transversely spaced longitudinal bars, a series of longitudinally spaced transverse floor rails extending across and beyond the sides of said bars, vertically disposed corner gussets joining the rails and bars, a transverse rail spaced vertically beneath each of the before mentioned rails and secured to said gussets, end gusset plates joining superposed rails at both ends thereof and adapted for supporting connection with the vehicle side walls, road gear supporting brackets carried by the gussets of two pairs of cooperating rails near the front and rear, respectively, of the vehicle, supplementary longitudinal bars bridging the space between the rails of each of said pairs in vertically spaced relation to the first mentioned bars and a vertically disposed stiffening plate connecting the superposed bars.

4. In a motor vehicle having side walls and a roof, a base frame including a front and a rear load supporting buck, each comprising a pair of longitudinally spaced transversely extending open frame sub-assemblies made up, respectively, of a pair of vertically spaced rails and vertically disposed gusset plates joining the opposite ends of said rails for load receiving connection with the side walls and adapted for support on the vehicle road gear and a series of similar sub-assemblies located between the front and rear bucks and suspended at opposite ends from the side walls

for cooperation with the first mentioned sub-assemblies in supporting a floor.

5. In a motor vehicle having a roof and side walls, a base frame including a series of transversely extending sub-assembly units, longitudinally spaced apart and each comprising a pair of vertically spaced rails connected by gusset plates and joined at opposite ends to the side walls, certain of said units being suspended from and transferring their load into the side walls and others receiving the load from and suspending the side walls and being arranged at the front and the rear of the vehicle in pairs with the sub-assembly units of one pair cooperating to receive the forward running gear therebetween and

the units of the other pair cooperating to receive the rearward running gear, shackle brackets carried by the gusset plates of the sub-assembly units of said pairs and through which the load is transmitted into the running gear, longitudinally extending tie bars connecting the units of each pair in bridging relation to the associated running gear and being arranged in transversely spaced sets of two vertically spaced bars fastened to adjacent gusset plates and a stiffening plate joining the vertically spaced bars of each set and cooperating therewith to resist relative displacement of the interconnected cooperating units.

HAROLD E. FOX. 15
